DESIGN FOR A TRAILER TANK

Ralph D. George, Kansas City, Mo., assignor to
Butler Manufacturing Company, Kansas City,
Mo., a corporation of Missouri

Application October 9, 1937, Serial No. 72,092

Term of patent 14 years

To all whom it may concern:

Be it known that I, Ralph D. George, a citizen of the United States, residing at Kansas City, in the county of Jackson and State of Missouri, have invented a new, original, and ornamental Design for a Trailer Tank, of which the following is a specification, reference being had to the accompanying drawing, forming part thereof, in which

Figure 1 is a perspective view of a trailer tank, showing my new design.

Figure 2 is a side elevation of the tank shown in Figure 1.

Figure 3 is a top plan view of the trailer tank shown in Figure 1.

Figure 4 is a rear end view of the trailer tank shown in Figure 1.

I claim:

The ornamental design for a trailer tank substantially as shown.

RALPH D. GEORGE.
